UNITED STATES PATENT OFFICE.

RICHARD SMITH, OF SHERBROOKE, QUEBEC, CANADA.

DOCTOR FOR PAPER-CALENDER ROLLS.

SPECIFICATION forming part of Letters Patent No. 352,665, dated November 16, 1886.

Application filed May 27, 1886. Serial No. 203,413. (No model.)

To all whom it may concern:

Be it known that I, RICHARD SMITH, a citizen of the Dominion of Canada, residing at Sherbrooke, in the county of Sherbrooke and Province of Quebec, Canada, have invented certain new and useful Improvements in Doctors for Paper-Calender Rolls; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to "doctors," so called, particularly that class employed as deflectors or guides to lead a continuously-traveling endless paper web between and partially around a series of calender rolls in rapid rotation.

My improvements pertain more especially to the use of doctors employed in the method for guiding an endless paper web between a stack of rolls, which is fully described in Letters Patent No. 327,031, issued to myself on the 29th day of September, 1885. In this invention a system of feed-pipes was arranged longitudinally of and in parallelism with the face of the rolls, alternating upon each side and adapted to deliver a current of air in the direction of the endless paper web as it passes between the rolls in the act of leading it therethrough.

One feature in my invention is embodied in constructing the upper thickened portion or back of the doctor hollow, and perforating it lengthwise upon the inner side, or that contiguous to the face of the rolls with which it co-operates, so that it may deliver a continuous supply of air.

A second feature is in pivoting said doctors so that they may be swung away independently from the face of the rolls, while a third feature consists in the particular arrangement of uniting them by adjustable eccentrics to an actuating lever-rod, whereby the entire series of deflectors or doctors may be simultaneously operated to approach, contact with, and there be maintained to co-operate with the calender-rolls during the passage of the endless web around and between the latter. By this same mechanism a converse movement of said

doctor can be effected to remove the latter from the rolls in case of repairs or any other existing cause which might require such movement. 55 If so desired, the deflectors may be caused to approach and contact with the rolls only during the time when the web is being conducted through and between them and then withdrawn; but in practice I find the surface of the 60 rolls is very materially improved by continuous contact of the deflectors or doctors thereupon. Lastly, in the spring-mounting of the supporting ends of each doctor, whereby when actively employed the latter is kept in continuous contact with the periphery of a roll; 65 hence if the roll rises, owing to a wad of paper or other material passing between said roll and the next adjacent lower one, the doctor, spring-actuated, rises with it and prevents 70 said obstruction from passing up and around the upper roll; hence the wad is compelled to advance downward and continues its passage, as is desired.

The drawings accompanying this specification represent in Figure 1 a perspective view of a portion of a stack of rolls provided with deflector-plates and actuating mechanism embodying my improvements, while Fig. 2 is a transverse section of said stack, looking toward the back side of the paper-machine of which they form a part. Fig. 3 is a perspective view, and Fig. 4 a vertical section, of the device for spring-mounting the doctors. Fig. 5 is a similar section taken transversely on 85 line $x-x$ of Fig. 4, while Fig. 6 is a plan of the actuating-eccentrics, their shaft, and the adjustable rods connecting them with the series of doctors. Fig. 7 is a transverse section of a deflector-plate in an active position with a portion of two co-operating rolls. Figs. 8 and 9 represent the manner of pivoting and uniting the doctors to the air-supply pipe. Fig. 10 is a front elevation of the adjusting-journals of the doctor P, and Fig. 11 is a section on line 95 y-y of Fig. 10. Figs. 12 and 13 are respectively a front elevation and sectional elevation of the front journal of the doctor P', hereinafter described.

In said drawings, A A' represent the front 100 and rear standards or housings, which support a series of calender-rolls, B B' B'' B'', forming part of a paper-making machine. Said rolls are to be suitably operated, and are in-

tended to receive a continuously-traveling endless web between and partially around them in the process of "calendering," so termed.

Since my invention and the improvements 5 embodied therein pertain and are applied to a pneumatic system, I have disposed a tubular frame, C, to be supplied with a continuous current of air from some proper source. Supported by this frame and pivotally attached 10 thereto at their rear extremities are the deflector-plates or doctors D D', arranged in alternating series on each side of the calender-rolls and opposite the points of juncture of the latter with each other. The essential component parts of these doctors consist in a hollow back or rib, a, provided with a longitudinal bore, b, to which is secured a sheet of metal, c, perforated at d d and bent to conform to the curvature of the roll, which it 15 partially incloses. This back is further provided with supports e e', the rear one of which terminates in a flange, f, adapted to be bolted to a corresponding one, g, forming part of a sleeve, F, fitting about and movable upon the 20 vertical portion of the tubular frame C, whereby a swinging or pivotal movement is secured, and the doctors can be swung toward or away from the calender-rolls, or easily removed in case of needed repairs.

30 The curved deflector-plates or shields I prefer to make of two kinds of metal, employing steel for the upper portion, which is in contact with the face of the rolls when in active service, while the shield portion not in contact with the rolls may be made of brass or other analogous metal.

The flange g of the sleeve is furnished with T-shaped slots, to retain the heads of the bolts, and thereby permit adjustment thereon of the 40 flanged head f, which forms part of the doctor. Thus the position of the latter may be easily altered with respect to its roll. Adjustment of the flanged sleeves F F is obtained by means of split screw-clamps t.

45 The front supporting-arm, e, of each doctor is mounted upon a bracket, G, which corresponds in number to that of the doctors employed, or to the number of rolls in the calender-stack. Said brackets are capable of adjustment upon and are bolted to cheek-pieces I I, permanently attached to the inside face of the front standard, A. These cheek-pieces are likewise slotted at h h, and the proper position of the brackets is thereby easily and 55 readily obtained. Furthermore, these brackets are vertically slotted at i i, to receive similarly-formed projecting ribs, adapted to secure the movable gib j. Between the latter and the bracket are placed coiled springs k k, 60 while to maintain the gib in position and still to permit it vertical motion, induced by the springs, a bolt, l, is passed therethrough and fits loosely in the bracket.

65 The outer extremity or supporting end, e, of the deflector-plate or doctor terminates in a bracket, m, which rests on the movable spring-actuated gib k. Thus the action of the latter is

to maintain the doctor with which it co-operates normally in contact with a roll when the doctor is actively disposed. Removable 70 locking-pins o o are disposed in said brackets m m and engage the arms e e of the doctors. Thus in case the latter require to be swung away from the rolls for any purpose this movement can be easily accomplished by removing 75 said pins, when the doctor is free to swing.

To operate the entire series of doctors on each side of the roll-stack simultaneously and maintain them continuously in contact with said rolls, or to remove them therefrom, as 80 circumstances may require, I have arranged and combined together the following instrumentalities: This mechanism consists, primarily, in an upright or vertical post or shaft, J, which may be secured to the front standard in 85 any convenient position to enable the operative to easily alter the doctors to any position required. Upon this shaft are mounted a series of eccentrics or disks, n n' n'', to one of which is secured an actuating lever-bar, K. 90 These hubs, above mentioned, are securely affixed to and adjustable upon the shaft J, and are peripherally slotted to receive and hold circumferentially-disposed loose rings p p', (see Fig. 4,) which are furnished with radially-projecting screw-threaded rods q q', adjustably 95 united to right and left couplings r r. The latter engage with connecting-rods s s, secured to the doctors by the locking-pins o o, which fit in the bracket-arms m m. The doctors thus are 100 all united and co-operate simultaneously as an entirety and in a similar manner; but since the shaft J is upon one side of the standard A, the connecting-rods q' q'', which unite the doctors upon the opposite sides of the rolls, must 105 necessarily be of considerable length. After the paper web has been conducted downward between and partially around the series of rolls composing the calendar-stack it becomes necessary to compel it to pass out without 110 wrapping round either of the two lowest rolls, since there is always a tendency to that effect, generally aggravated by the electricity generated by the rapid rotation of the rolls. To obviate this difficulty I have oppositely arranged two doctors, P P', constructed in the 115 usual manner, and have adjustably mounted them both front and rear upon the standards A A'. The journal adjustment of the doctor P is shown in Figs. 10, 11 as composed of two 120 circular plates or disks, 2 3. The former or bracket portion is provided with a lateral shoulder, and thereby is firmly bolted to the standard A. Upon the plane face of this disk 2 is adjustably secured the face-plate 3, provided with an eccentrically-disposed bearing, 4, which receives the journal of the doctor P. This arrangement is duplicated both front and rear. Adjustment of said doctor relatively to its distance from the face of the roll is obtained by rocking the disk or bracket 2, while the disposition of said doctor angularly therewith is obtained by means of the face-plate 3, which is slotted at 5 5 and moves upon bolts 125 130

playing therein and adapted to clamp it to the bracket-disk 2 in any desired position. The front adjustment of the upper doctor, P', is somewhat similarly produced by means of a 5 plate, 6, affixed to the cheek-piece I, while a bearing-disk, 7, carrying the journal 8, in which said doctor is mounted, is affixed thereto by means of the slots 9 9 and the clamping-bolts which hold said disk 7 in any desired position. 10 This arrangement of parts is shown in Figs. 12 and 13 of the drawings. The rear support of this doctor P' is a simple pivot upon the rear standard.

I claim—

15 1. A deflector-plate or doctor composed of a tubular back or rib to which is secured a curved metallic plate, the latter provided longitudinally with apertures opening into the tubular rib, whereby a flow of air may be continuously discharged, substantially for purposes herein described.

20 2. Two continuously-rotating rolls, one partially inclosed by and the other in contact with a deflector-plate or doctor, in combination with said deflector-plate pivotally mounted and swinging in horizontal paths of movement toward or away from the rolls, for purposes herein set forth.

25 3. In combination with a series of continuously-revolving rolls, the pivotal spring-actuated deflector-plates oppositely and serially arranged on either side thereof, said deflector-plates alternating at the meeting surfaces of the rolls and adapted to supply air continuously, substantially for the purposes described.

30 4. In combination with a pair of revolving rolls, a pivotally-mounted doctor composed of a tubular back, to which is secured a curved metallic plate, the latter to contact against the upper roll and partially inclose but not touch the lower roll, substantially as herein stated.

35 5. The series of revolving rolls provided with a series of alternately oppositely-disposed pivotally-arranged doctors, in combination with the actuating-shaft, eccentric-disks, and connecting-rods united with the doctors, whereby simultaneous movements of the latter are effected, substantially as herein stated.

40 6. In combination with a series of continu-

ously-rotating rolls and the alternately oppositely-arranged doctors pivotally mounted, the doctors P P', secured upon the standards and permanently impinging upon their co-operating rolls, as and for purposes set forth.

45 7. The combination, with the curved plate e, perforated as described, and attached to a tubular rib, a, pivotally mounted, of the sliding gib j, bracket G, and actuating-rod J, with its connecting mechanism, all operating substantially as described.

8. In combination with a pair of revolving rolls adapted to receive and pass between them a continuous paper web, the doctors longitudinally disposed thereof, but oppositely inclined and adjusted to rest in contact with said rolls while in rotation, substantially as herein stated.

55 9. In combination with a pair of rolls, the deflector-plate D and the shaft J, provided with the eccentric-hub n, ring p, and screw-threaded rod q, the rod s, adjustably connected with the doctor by the coupling r, substantially as described.

60 10. The cheek-pieces I and the bracket G, which supports one end of the doctor D, in combination with the gib j, its springs k k, and the terminal support e of said doctor, whereby vertical movement thereof is obtained, substantially for purposes herein set forth.

65 11. In combination with two adjacent rolls and the doctors vertically disposed as to each other, but oppositely and permanently inclined against the surface of said rolls, the adjustable disks 2 2 and face-plates 3 3, slotted at 5 5, and carrying the journals 4 4, all operating as herein described.

70 12. The combination, with two adjacent rolls and the oppositely-inclined doctors, longitudinally arranged and normally resting thereon, of the supporting-plates 6 6, slotted disks 7 7, and journals 8 8, substantially as and for the purposes stated.

In testimony whereof I affix my signature in presence of two witnesses.

RICHARD SMITH.
